United States Patent

Des. 234,916
Patented Apr. 15, 1975

234,916

PACKAGE OF SLICED FOOD OR THE LIKE

Ihor Wyslotsky, 3311 Montmartre Ave.,
Hazelcrest, Ill. 60429

Filed Jan. 15, 1973, Ser. No. 323,748

Term of patent 14 years

Int. Cl. D9—03

U.S. Cl. D9—192

FIG. 1 is an isometric view of a package of sliced food or the like embodying my new design;

FIG. 2 is a top plan view;

FIG. 3 is a side elevational view;

FIG. 4 is an end elevational view; and

FIG. 5 is a bottom plan view thereof.

I claim:

The ornamental design for a package of sliced food or the like, as shown.
